UNITED STATES PATENT OFFICE

HENRY HUNT, OF NEW YORK, N. Y., ASSIGNOR TO THE HARTFORD CARPET COMPANY, OF HARTFORD, CONNECTICUT.

DESIGN FOR CARPET.

SPECIFICATION forming part of Design No. 12,203, dated March 29, 1881.

Application filed February 7, 1881. Term of patent 3½ years.

To all whom it may concern:

Be it known that I, HENRY HUNT, of New York, in the county and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is the central figure of the design, and is a widely-open flower, somewhat like a rose. A stem connects the figure A with the figure B, which is circular in form, and has leaves projecting from one end, from which branch out two stems bearing the circular flowers a and b and the budding branch e. From the figure B also projects, on a stem, the flower-figure f, which has projecting from it, in turn, a stem bearing on it the leaf n and the bell-shaped flowers o. On another stem projecting from the figure B grow the leaves C and g, the flower i, and the circular flower h, with a leafy spray projecting therefrom, and on this same stem is set the circular rosette-shaped figure D, from which branches a stem bearing the hanging flower x, and another stem bearing the circular rosette-like flower E. On a continuation of the same stem is set the open-flower figure G, from which projects the vine T, bearing leaves and flowers. On another stem growing from the figure E is found the cup-shaped figure M, with a spray bearing leaves projecting therefrom, and from this figure E also projects a stem bearing the circular flower-figures m, and also the large open flower K, having a spray of star-shaped flowers p thereon, and extending to the circular flower-like figure L, and having also a stem, upon which grows the oval figure P, the figure V, in shape somewhat like a cornucopia, and still farther along the same stem the flower-figure Q. From this figure Q projects the fan-shaped figure R, with a leafy tuft growing therefrom, and also the bud-like figure S, from which last grows a branch bearing the circular flower t, and another branch bearing the rose-like figure r, which has a tuft of ball-shaped buds projecting therefrom. These flowers and vines are spread over a patterned background, and the general effect of the design is that of a vine running irregularly over this background of regular pattern, the vine bearing upon it the various flowers, figures, and branches already described.
